CLAIM

The ornamental design for spout, as shown and described.

DESCRIPTION

FIG. 1 is a perspective view of our new design of the spout; FIG. 2 is a front elevational view of our new design of the spout;

FIG. 3 is a rear elevational view of our new design of the spout;

FIG. 4 is a top plan view of our new design of the spout;

FIG. 5 is a bottom plan view of our new design of the spout; FIG. 6 is a right elevational view of our new design of the spout; and,

FIG. 7 is a left elevational view of our new design of the spout.

The broken line representation in FIG. 1 of the drawings of the faucet base, handle and spout (partial) is for illustrative purposes only and forms no part of the claimed design.
